GLOVE

John Henry Whitcraft, New Bremen, Ohio, assignor to
Meco, Inc., Wichita, Kans.

Filed May 24, 1965, Ser. No. 85,412

Term of patent 14 years

(Cl. D3—11)

FIG. 1

FIG. 2

FIG. 3

FIG. 4

FIG. 5

FIGURE 1 is a front elevational view of a glove showing my new design.

FIGURE 2 is a side elevational view thereof.

FIGURE 3 is a rear elevational view thereof.

FIGURE 4 is an enlarged fragmentary plan view of a portion of the palm thereof; and

FIGURE 5 is a cross sectional view taken on the line 5—5 of FIGURE 4.

The dominant feature of my invention resides in a multiplicity of three pointed raised stars randomly disposed over the palm and the front of the fingers of the glove.

I claim:

The ornamental design for a glove, as shown and described.
